UNITED STATES PATENT OFFICE.

ROBERT W. WALLACE, OF MONTESANO, WASHINGTON.

MOWING-MACHINE ATTACHMENT.

1,337,863.

Specification of Letters Patent. Patented Apr. 20, 1920.

Application filed November 25, 1919. Serial No. 340,481.

To all whom it may concern:

Be it known that I, ROBERT W. WALLACE, a citizen of the United States, residing at Montesano, in the county of Grays Harbor 5 and State of Washington, have invented a new and useful Mowing-Machine Attachment, of which the following is a specification.

This invention relates to attachments for 10 mowing machines, and particularly to that class of attachments known as fender rods.

In mowing machines as usually constructed, when heavy grass is being cut, it will collect in bunches, which when encountered 15 by the machine on its next round about the field, very frequently clog the knives. When this occurs, the farmer has to stop his team and pull the clogged grass out with his hands. This, of course, results in a loss of 20 time and is very annoying.

The object of the present invention is to provide a rod which will press down all the cut grass, hay or the like out of the way of the cutter bar, so that clogging will be im- 25 possible.

This object is attained by providing a rod secured loosely to the inner shoe of the cutter bar and to the underside of the tongue of the mower. This rod is so shaped as to 30 be out of the way of the horses' heels, and at the same time cannot catch in cut hay, but instead, will press the same down under the inner shoe or cutter bar as the machine goes forward.

The invention will be best understood 35 from a consideration of the following detailed description taken in connection with the accompanying drawing forming part of this specification, with the understand- 40 ing, however, that the invention is not confined to any strict conformity with the showing in the drawing, but may be changed and modified so long as such changes and modifications mark no material departure 45 from the salient features of the invention as expressed in the appended claims.

In the drawing,

Figure 1 is a perspective view of so much 50 of a known type of mower as is necessary for an understanding of the invention, with the attachment in place.

Fig. 2 is a sectional view of a portion of 55 the inner shoe showing its attachment with the rod which forms the present invention.

Fig. 3 is a sectional view of the connec-

tion of the rod with the tongue of the machine.

Fig. 4 is a top plan view of the rod by itself in the position of Fig. 1.

60

5 represents a tongue of a well known type of mowing machine, and 6 the inner shoe thereof. A rod 7 is secured to this tongue and shoe, but not rigidly.

The rod 7 is bent upwardly, as indicated 65 at 8, near one end thereof and is further given the bends designated at 9 and 10 intermediate its ends, the bend 9 being inwardly toward the tongue, and the bend 10 being forwardly, the extreme outer end of 70 the rod being connected to the tongue in advance of the connection of the draft devices thereto. These three bends together provide for such a disposition of the rod as will cause it to incline upwardly from 75 the inner shoe and toward the tongue and yet will not interfere with the whiffletree, will be out of the way of the horses' heels, and will press down all bunches of cut grass under the shoe or cutter bar as the 80 machine goes forward, so that clogging will not occur.

The connection of the rod to the inner shoe, as illustrated in Fig. 2, is a loose one. The shoe end of the rod is straight and has 85 screw threads 11, and spaced therefrom an annular shoulder 12. The shoe has the customary hole therein for the attachment of the usual short rod which is provided with all mowers. Such a hole is shown in the 90 patent to Dain No. 921955. This hole or bore provided on the point or toe of the inner shoe is taken advantage of by running the bent end 8 of the rod therethrough, with the shoulder 12 on the forward side, and a 95 nut 13 screwed down upon the screw threads 11. When this has been done, there will be a looseness or play between the base of the nut, the shoe, and the shoulder, so that the shoe may turn relatively to the rod when 100 it is elevated as in driving the machine along a road or the like. This looseness or play will also permit of the cutter bar being turned to cut high or low in the fields.

The forward end of the rod is slidably 105 secured to the underside of the tongue by means of a clip 14, fastened in any desirable way to the tongue. The rod can slide freely between the clip and the underside of the tongue. This construction is necessary be- 110 cause when rough ground is encountered there will be considerable vibration of the

tongue and also of the cutter bar, and the rod would be bent out of shape in a short time unless loosely held to the tongue.

As the machine advances through the field, the heavy bunches of cut hay are moved out of the way of the inner shoe instead of being caught thereby and forced into the cutter bar in a wad. The rod, when shaped as described, in no way interferes with the whiffletree and is entirely out of the way of the draft animals. Its loose connection at each end is of especial importance because it permits the operation of the machine without any interference whatever therewith and yet will positively prevent clogging of the knives, as has been described.

What is claimed is:—

1. In a mowing machine having a cutter bar provided with an inner shoe, the combination therewith, of a rod secured loosely at one end directly to said inner shoe and slidably secured near its outer end to the tongue of the machine, said rod being bent from its connection with the shoe first upwardly, then inwardly toward the tongue and then forwardly beyond the connection

of the draft devices to the tongue, whereby the rod is at all times clear of the heels of the draft animal.

2. In a mowing machine having a cutter bar provided with an inner shoe, the combination therewith, of a rod, having one end straight and passed through a hole in the shoe, means for securing said rod therein so as to allow relative movement of said rod and shoe, said rod being bent, in advance of its connection with the shoe, in an upward direction, then bent laterally toward the tongue, and then forwardly to a point in advance of the connection of the draft devices to the tongue whereby the rod is at all times clear of the heels of the draft animal, and means for loosely connecting the forward end of the rod to the underside of the tongue.

In testimony that I claim the foregoing as my own, I have hereto affixed my signature in the presence of two witnesses.

ROBERT W. WALLACE.
